Benjamin Broido INVENTOR.

BY *O. V. Thiele*
his ATTORNEY.

UNITED STATES PATENT OFFICE.

BENJAMIN BRODIO, OF NEW YORK, N. Y., ASSIGNOR TO THE SUPERHEATER COMPANY, OF NEW YORK, N. Y.

APPARATUS FOR SUPERHEATING STEAM.

Application filed November 23, 1922. Serial No. 602,741.

My invention relates to superheaters intimately associated with boilers, as distinguished with separately housed superheaters, and is concerned particularly with the question of keeping the degree to which the steam is superheated constant under varying load conditions. There is provided by this invention a means, fundamentally new as far as I am informed, and very simple and reliable of attaining this desirable end.

The invention is shown by way of illustration in the accompanying two sheets of drawings. Figs. 1 and 2 show my invention applied to a water tube boiler of the so-called horizontal type, the former figure being a sectional lateral elevation, and the latter being a view on line 2—2 of Fig. 1.

Fig. 3 represents a boiler of the so-called vertical water tube type with my invention in place.

The boiler of Figs. 1 and 2 is of a well-known type. The drum 1 has, extending down from it, the two parallel water legs or headers 2—2 connected to each other by the water tubes 3. This structure is enclosed in a housing 4 which also contains the furnace space 5. Burners 6—6 supply fuel to the furnace, the products of combustion being directed over the water tubes 3 by the baffles 7—7, and leaving for the stack by way of the connection 8. Steam generated in the boiler leaves drum 1 by means of pipe 9.

In a boiler of this and other types there is a certain shifting, which has been experimentally determined, of the relative amounts of evaporation occurring in the several portions as the load on the boiler changes. To illustrate this phenomenon, and aid in the discussion of the theory underlying my invention, I shall use the following little tabulation:

45	Per cent evaporation.		B. t. u. superheat.			
	Rating.		Rating.		Increase.	
	100 per cent.	200 per cent.	100 per cent.	200 per cent.	B. t. u.	Per cent.
50						
A.....	85	160	860	1,600	750	88
B.....	10	25	100	250	150	150
C.....	5	15	50	150	100	200
Totals.....	100	200	1,000	2,000	1,000	-----

We can think of the boiler tubes as included in three imaginary groups, the first, which we shall call group A, being nearest the furnace and generating, when the boiler is operating at 100% rating, 85% of the steam; the second or intermediate group, called group B, generating 10% of the steam at 100% rating; and the third group, farthest from the furnace and called group C, generating 5%. The figures appear in the first column of the table. We are not now concerned with the relative size of these groups.

If, now, the load be increased so that boiler operates at 200% rating, the amounts of evaporation occurring in the sections A, B, and C will no longer bear the relation of 85, 10, and 5 to each other, but will shift, the first section, A, doing relatively less work and the sections B and C relatively more.

In the tabulation this is indicated by the figures 160, 25, and 15, which illustrate approximately the re-distribution that occurs. It is assumed that the boiler efficiency and the amount of moisture in the steam remain constant.

The explanation, briefly stated, is that the first section A, will not absorb quite twice as much heat at the higher rating and that

therefore the gases reach sections B and C at

a higher temperature than at 100% rating

with a consequent great heat absorption by

those sections.

The bearing of this on the lack of uniformity of superheat under varying loads in installations as hitherto made will now be briefly pointed out. These variations are both in kind and in degree, that is, the superheat may rise or it may fall and by different amounts, with a change in the rating at

which the boiler is operated; and the place

where the superheater is located is an im-

portant factor in this connection. As the

boiler is worked at higher ratings, a number

of factors are affected: The amount of the

hot gases generated in the furnace increases;

the rate at which these gases sweep over the

boiler and superheater surfaces increases;

the amount of steam generated increases;

the velocity of the steam through the super-

heater increases; there may be some rise in

the furnace temperature. These variations

affect the degree of superheat, no matter

what the location of the superheater. The

point, however, at which the superheater is located, is an additional factor which has an important effect on the variation in the superheat. As above pointed out, at higher ratings the gases reach the portions of the boiler, which are remote from the furnace, at a higher temperature than at lower ratings. A superheater located in proximity to such remoter portions will also receive the gases at such higher temperature at higher ratings and will, therefore, tend to give higher superheat with an increase in boiler rating. On the other hand, a superheater placed near the furnace will tend, as far as the location is concerned, to give lower superheat at the higher ratings.

My invention provides an arrangement whereby such variations may be eliminated.

In Figs. 1 and 2, the superheater elements 10, receiving steam from pipe 9 and header 11 through the subsidiary headers 12 (only one showing), and delivering it back to subsidiary headers 13 (also only one showing), and so to the header 14, extend through thimbles in the boiler water leg 2 into the spaces between the water tubes 3. They are so arranged that there is superheating surface adjacent to substantially every portion of the evaporating boiler surface.

If we think of the superheating surface as consisting of three sections—the first comprising those elements associated with boiler tube group A, the second of those associated with the boiler tube group B, and the third of those associated with boiler tube group C—then of every 1000 B. t. u. absorbed by the superheater at 100% rating of the boiler, the first section will absorb 850, the second 100 and the third 50 B. t. u.'s.

Now, if the rating is raised to 200% the relative heat absorption by the three superheater sections will not remain constant any more than does the relative evaporation in the three boiler sections, and for the same reason. The higher temperatures at which the gases reach the elements associated with groups B and C will cause them to absorb relatively more heat at the higher ratings; so that, as shown in the table, the three portions will not each absorb twice as much heat at 200% as at 100%, but will absorb respectively 1600, 250 and 150 B. t. u.'s, the shifting being parallel to that between the boiler sections. Instead of the total heat absorbed by the superheater being either more or less than twice what it is at 100% it will be just twice as much. For other ratings of the boiler, the redistribution of the heat absorption between the several superheater sections will likewise always be parallel to that occurring between the several boiler sections.

In installations as hitherto made, the variations affecting only a small portion of the boiler or a portion where perhaps only a very small fraction of the total steam was gen-

erated, and where, therefore, the effect of the variation on the total amount of steam was small, affected all of the superheater and caused disproportionately large variations in the amount of superheat. By distributing the superheater as I do, the variation in each part of the boiler is automatically accompanied by a corresponding variation for a portion of the superheater in which a proportionate amount of the superheating occurs. This automatically results in uniformity of superheat.

In practice, some concessions will at times have to be made to other considerations. For example, it will generally prove inadvisable to approach the furnace with superheating surface beyond a certain point, and for the sake of economy it will at times be advisable to omit some of the superheating surface in the upper end, where the amount of heat absorbed is small. Any such departure from the ideal arrangement (which is, to have the superheating surface so distributed that the conditions affecting each part of the boiler and varying for it shall affect an associated part of the superheater doing a corresponding amount of the superheating and vary for it in the same ratio as for the boiler part) will entail a corresponding loss of uniformity of superheat under variations of load. In practice it will prove generally satisfactory to have the superheater distributed through the boiler so that it is adjacent to a total of the boiler surface evaporating about 75% to 80% of the total amount evaporated.

To illustrate the application of my inventive idea to a boiler of a different type, I show it in Fig. 3 in a boiler with two upper steam and water drums, 21 and 22, and one lower drum 23, upper and lower drums being connected to each other by three banks of tubes 24, 25, and 26. The structure is enclosed in a housing 4^a. The products of combustion from the furnace 5^a are guided by baffles 7^a on their passage over the banks of tubes to the stack connection 8^a.

The superheater comprises the two headers 11^a and 14^a and the elements or units 10^a. The lengths constituting the several loops of the latter are arranged to extend parallel to the water tubes and are distributed from the proximity of the furnace through substantially all of the steam-generating surface of the boiler.

As my inventive idea is put into practice with different types of boilers variations will naturally occur; and I wish my appended claims to be interpreted to cover all such variations falling within the spirit of the invention.

What I claim is:

1. In a boiler the combination of extended heat-absorbing surface constituting a portion in which at least 75% of the steam is

- generated, a furnace the hot gases from which come into contact with said surface, and a superheater having an extended steam-superheating surface, the two surfaces being relatively so placed that each portion of each is adjacent to a portion of the other.
2. In a boiler the combination of extended heat-absorbing surface, constituting a portion in which at least 75% of the steam is generated, a furnace the hot gases from which come into contact with said surface, and a superheater having an extended steam-superheating surface, the two surfaces being relatively so placed that substantially each portion of the steam-generating surface has a portion of the superheating surface adjacent to it.
3. In a boiler the combination of extended steam-generating surface, a furnace the hot gases from which come into contact with said surface, and a superheater having an extended steam-superheating surface, the two surfaces being relatively so placed that each portion of that part of the steam-generating surface which generates substantially all of the steam has a portion of the superheating surface adjacent to it.
4. In a boiler the combination of extended heat-absorbing surface constituting a portion in which at least 75% of the steam is generated, a furnace the hot gases from which come into contact with said surface, and a superheater having an extended steam-superheating surface, the two surfaces being relatively so placed that each portion of that part of the steam-generating surface
- which generates the greater part of the steam has a portion of the superheating surface adjacent to it.
5. In a boiler the combination of extended heat-absorbing surface constituting a portion in which at least 75% of the steam is generated, a furnace the hot gases from which come into contact with said surface, and a superheater having an extended steam-superheating surface distributed adjacent to the water-heating and steam-generating surface from the point of entry of the hot gases to the point of their exit.
6. In a boiler the combination of a plurality of parallel water tubes constituting substantially all the steam generating surface of the boiler, a furnace, means to cause hot gases from the furnace to flow in contact with said tubes, and superheater tubes arranged between the water tubes and distributed substantially uniformly from the point where the gases first leave the furnace and come into contact with the tubes to the point where they leave them.
7. In a boiler, the combination of extended heat absorbing surface constituting a portion in which substantially all of the steam is generated, a furnace, the hot gases from which come into contact with said surface, and a superheater having an extended steam superheating surface, the two surfaces being relatively so placed that each portion of each is adjacent to a portion of the other.

BENJAMIN BROIDO.
